Inventor:

John M. Christopher

UNITED STATES PATENT OFFICE.

JOHN M. CHRISTOPHER, OF BALTIMORE, MARYLAND.

ALARM FOR VEHICLES.

SPECIFICATION forming part of Letters Patent No. 536,017, dated March 19, 1895.

Application filed March 10, 1894. Serial No. 503,121. (No model.)

To all whom it may concern:

Be it known that I, JOHN M. CHRISTOPHER, a citizen of the United States, residing at Baltimore, Maryland, have invented certain Im-
5 provements in Signal-Whistles for Street-
Railway Cars, of which the following is a
specification.

The object of my invention is to apply to
street cars a whistle adapted to be moved in
10 such position by means of the motor man's
foot so as to bring it in communication with
a motor as will hereinafter appear.

In the further description of the said in-
vention which follows reference is made to
15 the accompanying drawings forming a part
hereof, and in which—

Figure 1 is a longitudinal section of a por-
tion of a car to which is applied my improved
20 whistle. Fig. 2 is a cross section of Fig. 1
taken on the dotted lines $x-x$. Figs. 3 and
4 are enlarged details.

Similar letters of reference indicate similar
parts of the drawings marked thereon.

Referring to the drawings A is the car plat-
25 form; B, the axle, and C the wheels.

D is a fan or blower of ordinary description
secured to the platform A.

E is an electric motor fastened to the plat-
form of the car and in alignment with the
30 blower D. The fan in the blower is placed on
the shaft a of the motor E.

F is a treadle sustained in an elevated po-
sition by means of a spring b confined end-
wise between the foot piece c and the plat-
35 form of the car. The lower end of this treadle
terminates in a longitudinal arm d the outer
end of which is formed into a ring e .

G is a whistle placed within the ring e of
the arm d and secured thereto and adapted
40 to move bodily, so that the whistle orifice may
move into and out of communication with the
opening of the blower D.

H is an insulated wire leading from the trol-

ley, not shown. The lower end of this wire
is connected to the lower end of the treadle 45
F, and on the depression of the treadle con-
nection is made with the motor. Connection
is broken when the treadle rises by means of
the spring b , and on the removal of the motor-
man's foot.

Supposing the car to be in motion and the
motor man wishes to give a signal or blow the
whistle he places his foot on the foot piece of
the treadle and presses it down. In this move-
ment the wire H leading from the trolley is 55
brought in contact with the motor thereby
setting the motor in operation which also sets
the fan or blower in motion. At the same
time the whistle is carried down with the
treadle which places the whistle in communi- 60
cation with the blower and thereby a blast is
produced, as long as the treadle is kept in this
position; but if short blasts are to be sounded
the treadle is released by the foot which with-
draws the whistle from communication with 65
the blower when the fan may revolve without
any sound, and then forced down in rapid
succession in which movement the whistle is
brought in communication with the blower,
and when released cut off therefrom. 70

I claim as my invention—

1. In combination with a streetcar, a whistle
dependent from a vertically moving treadle
combined with a blower or fan in the path of
the moving whistle and means whereby the 75
blower or fan is put in operation, substantially
as specified.

2. In combination with a street car, a whistle
dependent from a vertically moving spring
held treadle combined with a fan or blower 80
which is put in operation as the treadle is de-
pressed, substantially as specified.

JOHN M. CHRISTOPHER.
